SWITZERLAND, ASSIGNORS TO FIRM OF ADOLPH SAURER, OF ARBON, SWITZER-
LAND.

ROAD-SPRINKLER.

1,376,108.

Specification of Letters Patent. Patented Apr. 26, 1921.

Application filed July 22, 1916. Serial No. 110,700.

To all whom it may concern:

Be it known that we, HEINRICH MAYER, residing at 701 Villa in den Reben, Arbon, Switzerland, GUSTAV SCHLATTER, residing at 5 408 Berglistrasse, Arbon, Switzerland, and ADOLF BALTENSWEILER, residing at Bahnhofstrasse 40, Arbon, Switzerland, have invented a new and useful Road-Sprinkler, of which the following is a specification.

10 Our invention relates to improvements in road sprinklers in which the sprinkling width as well as the output can be regulated independently.

Reference is to be had to the accompanying drawings in which:

Figure 1 is a longitudinal section of the cylinder of the sprinkler and an elevation of the levers, etc., for regulating its sprinkling width and output; Fig. 2 is a cross-section on line 2—2 of Fig. 1; Fig. 3 is a longitudinal section of the sprinkler cylinder showing its valve in another position than in Fig. 1, the controlling levers, etc., being left out; Fig. 4 is a section on line 25 4—4 of Fig. 3; Fig. 5 is an elevation illustrating an arrangement of regulating levers, etc., for cars where two men are in charge, and Fig. 6 is a section of a detail of said lever arrangement.

30 Referring now to Figs. 1 to 4, 1 is the cylinder of the sprinkler to which water is supplied through a pipe 2 at one end. The cylinder 1 the axis of which extends lengthwise of the car as customary has a number 35 of perforations 3 over which moves a piston valve 5 having a sector 6. The rod 15 of the piston valve is passed through a stuffing box 37 in the cover 38 of cylinder 1. A washing-spray 4 is formed on the underside 40 of cylinder 1.

Arranged in suitable bearings 39 in front of the driver's seat is a shaft 20 on which two levers 7 and 16 are free to move.

45 Lever 7 has a short arm 8 which is connected to a bell-crank lever 10, 11 by means of a rod 9. The bell crank lever is pivoted in a suitable bearing 40. A rod 12 connects said bell-crank to a lever 41 made with a sleeve 13 which is seated on the square end 50 14 of piston rod 15, the opening of the sleeve being of square cross section. It will be seen that when lever 7 is moved, the piston rod and with it piston 5 and sector 6 will be caused to turn.

The other lever, 16, is, by a rod 17, connected to a double armed lever 18, 19 pivoted in a bearing 42 which may be cast to the cylinder cover 38. The arm 19 of this double-armed lever has a slotted or forked end 43 which engages a pin 44 on a sleeve 60 15' which is held to move lengthwise with the piston rod 15 (yet is loose so that the said rod may turn relatively to the sleeve) so that by moving lever 16 the piston valve 5 is caused to slide in its cylinder. 65

In the position indicated in Fig. 1, the valve 5 and its sector 6 close all the perforations 3. If, by moving lever 7, the valve 5 is turned in the direction of the arrow in Fig. 2, it will be seen that it successively 70 opens all the horizontal rows of perforations except the holes in the last five vertical rows to the left in Fig. 1 which still remain closed by piston 5. In order to open these, lever 16 is moved in the direction of the arrow 75 until piston 5 is at the left hand end of its stroke, see Fig. 3.

It will be obvious that if the sector 6 is turned from the position shown in Figs. 1 and 2, in which it closes all the rows of perforations 3, it will first uncover only one horizontal row of perforations, so that only 80 a narrow width of the street or road will be sprinkled. As the sector is turned farther to uncover more horizontal rows of perforations 3, the width of the road portion reached by the water discharged through these perforations will of course increase, until, with the sector in the position shown in Fig. 4, the full sprinkling width is attained. 85 On the other hand, if with the sector 6 turned to a fully or partly open position, this sector, together with the valve 5, is moved lengthwise (without turning), it will be obvious that the sprinkling width 90 will remain unaltered, but the total amount of water discharged, that is to say, the output of the sprinkler, will be increased or diminished according as such longitudinal movement causes the valve to uncover or 95 cover additional vertical rows of perforations 3. It will be seen that in this manner the driver is enabled to regulate the sprinkler within certain limits to any desired ratio of output and sprinkling width. 100

To open the washing spray 4 valve 5 is moved to the right hand end of its stroke by means of lever 16 where it closes all the

perforations 3 but opens the port of the washing spray.

When two men are in charge of the car, we prefer to so construct and arrange the controlling levers that they can be manipulated by either of them.

With this object in view, we make the shaft 20 so long that it extends over the entire width of the car frame 26. The seat of the 10 driver is indicated at 29, with the steering wheel 36 in front of it, while the seat of the attendant is on the other side of the car, at 35. The arrangement is such that the main output of both sprinkling cylinders is regulated by the same lever while the sprinkling width is regulated by a separate lever for 15 each cylinder. It follows that while the main output will always be equal for both cylinders the sprinkling width of either 20 cylinder may be regulated separately.

The lever 16 for regulating the output is arranged between the seats of the driver and his attendant so as to be within easy reach of both men.

25 We further provide two sleeves 22 and 23, which are keyed to, and a third sleeve 21 which is loose on, the shaft 20. Also keyed on shaft 20 is an arm 33, and a similar arm 34 is formed on sleeve 21. These arms correspond to the short arm 8 of lever 7 in Fig. 1 and each of them is connected to the piston rod 15 of the valve 5 in one sprinkling cylinder 1. The connecting means may be the same as those illustrated in Fig. 1.

30 Each of the sleeves 22 and 23 is provided with a conical socket 45 and 46, respectively, while sleeve 21 has two sockets 24 and 25. One of these sockets, say 45, is illustrated on an enlarged scale in Fig. 6. The sockets 40 are adapted to receive one of two controlling levers 27 or 28 which have tapered ends 32 fitting into the sockets. A key 31 is provided on the tapered end of either controlling lever, and a corresponding key-way 47 is formed in each of the sockets. A threaded ring 30 may be screwed into the upper portion of each socket so as to hold the controlling lever in position.

35 In Fig. 5, it is assumed that the driver is to manipulate all the controlling levers. Lever 27 is introduced into the socket 25 at his left, and lever 28 into the socket 46 at his right hand side. By means of lever 27, he regulates the sprinkling width of one 45 cylinder, and by lever 28 independently that of the other while by lever 16 he regulates the output of both cylinders simultaneously. It will be seen that, in the full lines position, lever 27 would be practically out of the attendant's reach. Therefore, if the attendant is to manipulate the controlling levers, lever 27 is introduced into socket 24 at the right and lever 28 into socket 45 at the left hand side of the attendant, as illustrated in dot and dash lines in Fig. 5. Both levers 27 and

28 may also be introduced into sockets 24 and 46 so as to enable either the driver or the attendant to manipulate them. It follows that by this arrangement a variety of positions for the controlling levers is given of 70 which the most suitable one may be selected under any conditions.

75 Preferably, we so construct the sockets and levers that the levers will face in the same direction always, even when transferred from one socket to another. We are thus enabled to provide said levers with inscriptions such as "Open," "Shut," etc., on that side which is visible to the men in any position of the levers.

80 Since our invention enables the driver or attendant not only to slide the valve 5, 6 in its cylinder 1 and to turn it as well but also to slide it without turning and vice versa not only the absolute values of output and sprinkling width can be regulated but also their ratio; so that it is possible, for instance, to adapt the sprinkling width to given conditions—broad or narrow streets, etc.—thus increasing the usefulness 85 of a car provided with the sprinkler.

85 A further advantage is that by the same axial displacement of valve 5 which controls the output the port 4 for the washing spray is also controlled. As mentioned above, the 90 washing spray can be operated only after all the perforations 3 have been closed by valve 5 and sector 6, see Fig. 1.

95 It will be observed that while the perforations 3 for the spray are at one side of 100 the respective cylinders or sprinkler heads 1, the ports 4 for the washing spray or jet are located at the bottom of these heads or cylinders. We thus avoid the danger of having the spray from the perforations 3 105 sweep back to the cleaned portion of the street or road, the matter forced to one side by the jet from the port 4.

We claim:

1. In a road sprinkler car, sprinkling 110 heads or cylinders located on different sides of the sprinkler car, independent means for controlling the sprinkler heads on different sides, and operating levers for said means, said levers being transferable from positions near the longitudinal center of the 115 sprinkler car to positions near the sides thereof, to facilitate control of the sprinkling operation by an attendant stationed at either the left or the right of the car. 120

2. In a road sprinkler, a cylinder having means for supplying water thereto and provided with perforations, a valve arranged to coöperate with said perforations, two sockets mounted to turn independently 125 about the same axis, means, connected with one of said sockets, for effecting a relative turning movement of the valve and cylinder, means, connected with the other socket, for effecting a relative longitudinal move- 130

ment of the valve and cylinder, actuating levers, and means for securing said levers in said sockets detachably.

3. In a road sprinkler, in combination, 5 a plurality of cylinders, means for supplying water to said cylinders, perforations in said cylinders, a valve in each cylinder, adapted to coöperate with said perforations, a controlling shaft, a lever mounted loosely 10 on said shaft and adapted to shift said valves lengthwise in said cylinders, sockets keyed to said shaft on one side of the car and connected with means for turning one 15 of said valves or one set of said valves within one of said cylinders or one set of said cylinders, a sleeve mounted loosely on said shaft on the other side of the car and having two sockets connected with means for turning the other valve or the other set 20 of said valves within the other said cylinder or the other set of said cylinders, levers adapted to be received in said sockets, and means for securing said levers in said 25 sockets.
4. In a road sprinkler, in combination, 30 a cylinder, means for supplying water to said cylinder, perforations in said cylinder, a valve in said cylinder adapted to coöperate with said perforations and a port connected with a washing spray and adapted to be opened and closed by said valve, said port being located in the cylinder between said perforations and the water-supply con-

nexion, so that the valve, when shifted to connect the spray with the water-supply, 35 will move toward and over said perforations.

5. In a road sprinkler, a plurality of sprinkler heads, a valve for each sprinkler head, unitary means for effecting at the 40 same time, a relative longitudinal movement of the several valves and their heads, and a plurality of means, independent of each other and of said unitary means, for effecting separately, a relative turning movement 45 of any one of said valves and its head.

6. In a road sprinkler, a head having means for supplying water thereto and provided with perforations at one side, said port being of much greater cross section 50 than any one of said perforations, and with a discharge port at another side, a valve controlling said perforations and said port, and means for effecting a relative movement of said valve and head. 55

7. In a road sprinkler, a head having means for the supply of water thereto and provided with a washing spray port at the bottom and with perforations at one side, and single means for covering and uncover- 60 ing said port and perforations.

In testimony whereof, we have signed this specification.

HEINRICH MAYER.

GUSTAV SCHLATTER.

ADOLF BALTENSWEILER.
